UNITED STATES PATENT OFFICE.

THOMAS F. BARRETT, OF SOUTH POTTSTOWN, PENNSYLVANIA.

POWER TRANSMISSION AND STORAGE APPARATUS.

1,352,936.

Specification of Letters Patent. Patented Sept. 14, 1920.

Application filed August 5, 1919. Serial No. 315,564.

To all whom it may concern:

Be it known that I, THOMAS F. BARRETT, a citizen of the United States, residing in South Pottstown, Pennsylvania, have invented Power Transmission and Storage Apparatus, of which the following is a specification.

One object of this invention is to provide a relatively simple, compact and reliable device for utilizing the force available in a moving train for the operation of apparatus such as pumps, switches, signals, etc., adjacent the track on which such train operates;—the invention more particularly contemplating mechanism actuated by the wheels of a locomotive and cars for raising a weight which is utilized in operating any desired device or mechanism.

A further object of the invention is to provide a device of the character described with novel means for preventing damage when the weight has been elevated to a predetermined height and for thereafter insuring that the weight shall be again actuated by a moving train after it has fallen or when it is allowed to drop from such a position.

Another object of my invention is to provide a novel mechanism for utilizing the wheels of a train for winding upon a drum a weight-carrying cable, together with means for automatically disconnecting the drum from the train-actuated member after the weight has been elevated to a predetermined height and for thereafter again automatically connecting the drum and said member when the weight has fallen to a predetermined extent.

These objects and other advantageous ends I attain as hereinafter set forth, reference being had to the accompanying drawings, in which,

Figure 1 is a side elevation, to some extent diagrammatic, illustrating the detail construction of my invention;

Figs. 2 and 3 are side elevations of portions of the mechanism shown in Fig. 1.

In the above drawings 1 represents one of the rails of a railroad and 2 a car or locomotive wheel operative thereon. Adjacent this rail a lever 3 is mounted upon a fulcrum or pivot structure 4 and has one arm 5 extended upwardly along the outer side of the rail 1 in such a position that it is automatically depressed by a wheel rolling over the same. The effective width or wheel engaging portion of this arm 5 may be varied as desired

so that it will be depressed either by every wheel passing over the rail 1, or, by reason of its lateral extension as shown in Fig. 3, will be held in a depressed position by one 60 wheel until it has been engaged by the one or two other wheels on the same car truck.

In the former case the lever 3 will be oscillated by each wheel that engages its arm 5 and in the latter case it would be oscillated 65 once by each set or series of wheels passing over said arm.

The outer end or second arm of the lever 3 is operatively connected through a pin 6 to a movement-magnifying device, such as a 70 lazy tongs 7, in such manner that an upward movement of said arm from its lower position will cause the lazy tongs to be extended or projected longitudinally, while the reverse movement will cause retraction of this device into the position shown in Fig. 1. In the present case the lazy tongs 7 is extensible in a substantially horizontal line and its outer or free end is supported by a roller 8 operative upon a flat inclined structure 9, 80 being connected through a link 10 with a toothed rack 11 longitudinally guided at the bottom of a tower or post structure 12.

This same structure is provided with bearings for a shaft 13 on which is loosely 85 mounted a toothed wheel or gear 14 meshing with or engaged by the teeth of the rack 11 and carrying a pawl or dog 15. The latter is designed to coöperate with a ratchet wheel 16 fixed to the spindle 17 on which the gear 14 is carried and on which is also fixed a pulley wheel 18. Through a belt or chain 19 this pulley wheel, which is mounted at the bottom or lower end of the post structure 12, is operatively connected to a second pulley 95 wheel 20 at or adjacent the top of said structure where it is fixed to a shaft or spindle 21 mounted in suitable bearings 22.

This spindle, in addition to being rotatable in these bearings, is longitudinally 100 movable to a limited extent and is mounted in alinement with a second shaft or spindle 23 carried in bearings 24, the parts being so arranged that when in one position the shaft 21 may be operatively coupled to the shaft 105 23 through a suitable clutch 25.

The shaft 21 is acted on by a spring 26 in such manner that it tends to move away from the shaft 23 so as to release or open the clutch 25 and in order that the effect of 110 this spring may be overcome and the shaft 21 moved toward and coupled to the shaft

23, I hinge or pivot a movable arm 28 to a supporting structure 29 and extend it across the outer end of the shaft 21, connecting its free end through a cable 30 with a carriage 31 vertically guided on a bar or rod 32 adjacent the bottom of the post structure 12.

This carriage is so placed as to be acted on by a cam in the form of a bent rod or bar 33 connected to and movable with the toothed rack 11, being so formed as to permit the spring 26 to raise the carriage 31 and, through the shaft 21, release the members of the clutch 25 only when the lever arm 5 is not engaged by the wheels 2 and when the lazy tongs 7 occupies a correspondingly collapsed or retracted position. When however the arm 5 is depressed and the lazy tongs 7 is extended, the cam 33 so acts on the carriage 31 as to draw the arm 28 toward the shaft 21 and force the latter toward the shaft 23 so as to cause closing of the clutch 25.

The cam bar 33 is so connected to the toothed rack 11 as to be capable of movement toward and from the same under the action of the carriage 31 in case this is not free to move on its guideway 32, and for this purpose I extend the ends of said cam bar substantially perpendicular to said toothed rack through which they extend, and mount springs 35 between their heads and said rack so that no part of the device will be broken or unduly strained under the conditions above noted.

Fixed to the shaft 23 is a winding drum 36 for the reception of a cable 37, which carries a weight 38 of a mass sufficient to store power for the operation of such apparatus as switches, signals or the like. Such weight would preferably though not necessarily be operative within the hollow of the post structure 12 and would have mounted adjacent the upper end of its path of movement a device, such as a lever 39, whereby the clutch 25 would be automatically opened or released, with a view to preventing further winding of the cable 37 on the drum 36 by the action of the shaft 21 when said weight has been raised to a predetermined height.

For this purpose one arm of the lever 39 is extended to operate upon a disk 40 fixed to the shaft 21, and a second arm is acted on by a spring 41 in opposition to the weight 38 so that when the latter occupies any but its highest position, the lever 39 is drawn away from the disk 40 far enough to permit closure of the clutch 25. The mechanism to be operated by the falling of the weight 38 is actuated through a pulley 42 fixed to the shaft 23 and it will be understood that such mechanism would preferably include any suitable form of governing device (not shown) whereby the rate of fall of the weight would be regulated as desired.

Under operating conditions the passage over the rail 1 of a wheel or set of wheels such as would be mounted on the truck of a car, would cause depression of the arm 5 of the lever 3 and an elevation of the free end of said lever. The lazy tongs 7 would thereupon be extended and the longitudinal movement of the rack 11 would cause rotation both of the toothed wheel 14 and, through the pawl 15 and ratchet 16, of the pulley 18. Through the belt 19 the pulley 20 and shaft 21 would likewise be turned and since shortly after the beginning of the outward movement of the rack, the cam bar 33 would draw down the carriage 31 upon its guide 32, said shaft 21 would be moved toward the shaft 23 to which it would be operatively connected by the clutch 25.

As a consequence this second shaft would be turned, the cable 37 would be wound upon the drum 36 and the weight 38 would be raised to a certain height, where it would be held by the governing mechanism connected to the shaft 23. As soon as the wheel or set of wheels disengage the arm 5 of the lever 3, the lazy tongs 7 and said lever return to their normal positions with the clutch 25 open as shown in Fig. 1 where they remain until another wheel or set of wheels causes the above described operations to be repeated, it being noted that the return movement of the toothed rack 11 causes the gear 14 to rotate without turning the pulley 18 by reason of the disconnecting action of the pawl 15.

As a complete train of greater or less length passes the above described apparatus, there are thus delivered to the latter a succession of impulses each resulting in a greater or less rotation of the drum 36 and the intermittent raising of the weight 38 until finally this comes into engagement with the lever 39, and against the action of the spring 41, so acts upon the disk 40 as to move the shaft 21 in its bearings sufficiently to disconnect or open the clutch 25. Thereafter the shaft 21 is rotated by the passage of the train over the lever 3 without affecting the shaft 23, although the longitudinal movement of the rack 12 causes movement of the cam bar 33 relatively to the carriage 31. Since however this cannot cause longitudinal movement of the shaft 21 toward the shaft 23, the springs 35 yield to allow movement of said cam bar away from the rack when the rollers 44 of said carriage engage that portion of said bar nearest the rack.

When by reason of the operation of the driven mechanism connected to the shaft 23, the weight 38 again falls so as to disengage the lever 39, the cam bar 33 through the cable 30 will again become effective to couple said two shafts 21 and 23 and cause raising of the weight each time the lever 3 is ac-

tuated by a passing wheel or set of wheels. Under normal conditions however, when the lever 3 occupies the position shown, the rollers 44 of the carriage 31 engage the inclined portion of the cam bar 33 and allow the spring 26 to retain the shaft 21 in such position that it is operatively disconnected from the shaft 23. The latter may thus be turned under the action of the weight 38 and caused to operate its associated mechanism without being required to turn the shaft 21 with the pulleys 20 and 18.

From the above description it will be noted that I have provided a relatively simple and inexpensive device whereby power may be conveniently transmitted from a moving train and stored for utilization in operating signals, small pumps or other mechanism at points where it would otherwise be a difficult and expensive matter to obtain power from any source. The apparatus itself is of such a nature as to be inexpensive to construct and maintain and is capable of operation for long periods of time with but little if any attention.

I claim:

1. The combination of a member positioned adjacent a railroad track to be actuated by car wheels passing thereon; a power storing device; means for intermittently connecting said member and said device in response to movements of the member by a series of car wheels; and means for automatically causing disconnection of said device from the member when the latter occupies a normal inoperative position.

2. The combination of a member mounted adjacent a railroad track in position to be actuated by car wheels passing thereon; an element operatively connected to said member and reciprocated when the latter is actuated; a power storing device; with means for automatically connecting said device to said element while the latter is moving in one direction and automatically disconnecting it from said element when the latter moves in an opposite direction.

3. The combination of a member mounted adjacent a car track in position to be actuated by wheels passing thereon; two rotatably mounted shafts; a clutch for connecting said shafts; means for turning one of the shafts on said member; and a device actuated by the member for causing automatic release of the clutch when said member occupies its normal inoperative position.

4. The combination of a member mounted adjacent a car track in position to be actuated by wheels passing thereon; two rotatably mounted shafts; a clutch for connecting said shafts; means for turning one of the shafts on said member; and a cam car-

ried by the member for causing release of the clutch when said member occupies its normal inoperative position.

65

5. The combination of a member positioned to be operated by the wheels of a train; a device to be driven; a clutch one of whose elements is connected to said driven device; means including a movement-magnifying device connecting the other clutch element to the wheel operated member; and an automatic device for causing operative connection of the two elements of the clutch when the wheel operated member is moved in one direction.

70

6. The combination of a member mounted to be actuated by the wheels of a train; a lazy tongs connected thereto; a reciprocating member actuated by the lazy tongs; a shaft connected to be operated by said reciprocating element; a device to be actuated; a clutch for connecting said shaft to said device; and automatic means operated by said wheel-actuated member for governing the operation of the clutch.

85

7. The combination of a lever mounted to be actuated by the wheels of a train; a lazy tongs operated by said lever; a toothed rack connected to the lazy tongs; a gear engaging said rack; a shaft operatively connected to said gear; a device to be operated; and means for connecting said device to said shaft when the rack member is moved in one direction.

90

8. The combination of a member mounted to be actuated by the wheels of a train; a reciprocable element; a movement magnifying device connected between said element and said member; a shaft; means for causing said reciprocable element to rotate the shaft only when said wheel actuated member is moved in one direction; a power storing device; a clutch for connecting said device to the shaft; and means for causing closing of the clutch while said shaft is being turned by the wheel actuated member.

95

9. The combination of a member mounted to be actuated by the wheels of a train; a reciprocable element; a movement magnifying device connected between said element and said member; a shaft; means for causing said reciprocable element to rotate the shaft only when said member is moved in one direction; a power storing device; a clutch for connecting said device to the shaft; means for causing closing of the clutch when said shaft is turned; with a device for causing opening of the clutch when the shaft ceases to turn.
